UNITED STATES PATENT OFFICE.

DONAT CHAREST AND AIMER LAPOINTE, OF HULL, QUEBEC, CANADA.

SAFETY-RULE HOLDER.

Application filed August 6, 1921. Serial No. 490,394.

To all whom it may concern:

Be it known that we, DONAT CHAREST and AIMER LAPOINTE, both subjects of the King of Great Britain, and both residents of the 5 city of Hull, in the Province of Quebec and Dominion of Canada, have invented certain new and useful Improvements in Safety-Rule Holders, of which the following is a specification.

10 This invention relates to improvements in safety rule holders, and has for its objects to provide a holder especially adapted to be used to carry a folding carpenter's rule together with other small tools that

15 may be used by the worker.

Further objects are to provide a holder provided with resilient means to carry the folding carpenter's rule and to provide means whereby the body portion of the 20 holder can be carried in the pocket of the overall, being secured thereto by suitable means provided on the said body portion.

Further objects still are to provide a holder which consists of an inwardly tapered body portion provided with two resilient members secured in the side walls thereof and designed to engage the rule or tool 25 slipped therein.

Further objects still are to provide a 30 holder of simple construction and not liable to go out of repair, and generally to adapt the several parts to perform the functions required of them.

And it consists essentially of the 35 proved construction hereinafter described in detail in the accompanying specifications and drawings.

In the drawings:

Figure 1 is a perspective view of the 40 proved rule holder.

Figure 2 is a sectional elevation of the same.

Figure 3 is a vertical section taken at right angles to that shown in Figure 2.

45 Figure 4 is a sectional perspective view of the set screw used in combination with the improved rule holder.

In the drawings, like characters of reference indicate corresponding parts in all 50 the figures.

Referring to the drawings:

A represents the improved safety rule holder which consists of a body portion 10 having its side walls 11 and 12 tapered 55 downwardly and inwardly. The back wall 13 of the body portion 10 extends higher

than the other walls, and is formed on the back thereof with a projection 14 formed with a threaded recess 15. The recess 15 is designed to be engaged by the threaded 60 shank of a set screw 16. The rim of the head of the screw 16 is provided with indentations 17 designed to engage the cloth of the overall. The side walls 11 and 12 of the holder are provided adjacent the top 65 thereof with two leaf springs 18 and 19 riveted or otherwise secured thereto and having their lower ends in close relation to one another.

When this safety holder is used, the same 70 is carried inside or outside the overall pocket, and the projection 14 is passed through the buttonhole, being securely held therein by means of the set screw 16 which is driven into the recess 15 while the indentations 17 engage the cloth of the overall, 75 thus preventing the holder to turn on the shank of the screw 16 as an axis. The folding rule is then slipped inside the body portion and forcing the leaf springs 18 and 19 apart, slides between them and is held in the body portion by the lateral pressure exerted against the sides of the rule by the leaf springs 18 and 19.

It is obvious that a pencil could also be 80 carried by the holder by being slipped into sliding engagement with one of the leaf springs after the rule has been placed in the body portion. When either the pencil or the rule is taken off from the holder, the 90 same is pulled downwardly or upwardly if the holder be placed inside the pocket, and it will be seen that the remaining tool will be held inside the body portion by the springs 18 and 19 springing back to normal 95 position and thus engaging the pencil or rule remaining in the holder.

The body portion 10 is formed with side walls 11 and 12 being tapered inwardly so that more strength is thus provided in the 100 holder, which will thus have a minimum chance of being deformed.

It is obvious that the body portion 10 could be made of any desired material, but the same could be easily stamped in dies 105 and the sides being folded together could be welded so that the same would assume the form shown in Figure 1 of the drawings. If the body portion is to be made of one of the lighter materials such as aluminum, it 110 cannot be welded, but the same could be cast in the desired form.

As many changes could be made in the above construction and many apparently widely different embodiments of our invention within the scope of the claims, constructed without departing from the spirit or scope thereof, it is intended that all matter contained in the accompanying specification and drawings shall be interpreted as illustrative and not in a limiting sense.

10. What we claim as our invention is:

1. A safety rule holder comprising a body portion having its side walls tapering inwardly, resilient members carried by the said walls and designed to slidably engage the rule, one of the outer walls of the body portion being formed with a threaded recess, and a set screw on the recess as and for the purpose specified.

2. A safety rule holder comprising a body portion having its side walls tapering inwardly, resilient members carried by the side walls and designed to slidably engage the rule, a projection on the outer back wall of the body portion formed with a threaded recess, and a set screw engaging the recess as and for the purpose specified.

3. A safety rule holder comprising a body portion, having its side walls tapering in-

wardly, resilient members carried by the side walls and designed to slidably engage the rule, a projection on the outer back wall of the body portion formed with a threaded recess, a set screw engaging the recess, the set screw head being formed with an indentation, as and for the purpose specified.

4. A safety rule holder, comprising a body having its side walls tapering inwardly and downwardly, resilient members carried by the said side walls and designed to slidably engage the rule, the resilient members being adapted to have their lower ends normally bearing one against the other, the back wall of the body portion being formed with an extending portion, substantially higher than the remaining wall, a projection on the extension of the back wall formed with a threaded recess, a set screw engaging the recess, the head of the set screw being formed with a series of indentations.

In witness whereof we have hereunto set our hands in the presence of two witnesses:

DONAT CHAREST.
AIMER LAPOINTE.

Witnesses:

GEO. WALLINGFORD,
A. M. KENNEDY.
